DESIGN FOR A LIGHTING FIXTURE LENS OR THE LIKE ARTICLE

Joseph Levy, New York, N. Y., assignor to Century Lighting, Inc., a corporation of New York

Application June 25, 1938, Serial No. 78,053

Term of patent 7 years

To all whom it may concern:

Be it known that Joseph Levy, a citizen of the United States and resident of New York city, in the county of Kings and State of New York, has invented a new, original, and ornamental Design for a Lighting Fixture Lens or the Like Article, of which the following is a specification, reference being had to the accompanying drawing, forming part thereof, in which, Fig. 1 is a front elevational view of a lighting fixture lens

embodimenting the new design; Fig. 2 is a rear elevational view thereof showing only one-quarter of the ornamental portion and the outline in dot and dash lines, and Fig. 3 is a cross-sectional view taken on lines 3—3 in Fig. 1.

I claim:

The ornamental design for a lighting fixture lens or the like article, as shown.

JOSEPH LEVY.
